Primary Examiner — George J Ulsh
Assistant Examiner — Thanh Luu Wong(57) **CLAIM**

The ornamental design for a vaginal shield as shown and described.

DESCRIPTION

FIG. 1 is a front view of a vaginal shield showing my new design;

FIG. 2 is a rear view of the vaginal shield;

FIG. 3 is a right side view of the vaginal shield;

FIG. 4 is a left side view of the vaginal shield;

FIG. 5 is a top view of the vaginal shield;

FIG. 6 is a bottom view of the vaginal shield;

FIG. 7 is a top front side perspective view of the vaginal shield; and,

FIG. 8 is a rear view of the vaginal shield in a use position. The broken lines in FIGS. 1 through 7 illustrate a border of a portion of the vaginal shield, inside the border forming no part of the claimed design. The broken lines in FIG. 8 are illustrative of environmental structure forming no part of the claimed design. The dot-dash lines shown in FIG. 8 illustrate the boundaries of the environmental view and form no part of the claimed design.
